US00D541798S

(12) **United States Design Patent** (10) Patent No.: **US D541,798 S**
Ichida et al. (45) Date of Patent: ** May 1, 2007

(54) **DISPLAY WITH CONSOLE FOR
PROGRAMMABLE LOGIC CONTROLLER**

(75) Inventors: **Toshihiko Ichida**, Shizuoka-ken (JP);
Motoo Nasu, Shizuoka-ken (JP);
Toshiyuki Tsuji, Shizuoka-ken (JP);
Koyuru Nakano, Nara-ken (JP)

(73) Assignee: **Omron Corporation**, Kyoto (JP)

(**) Term: **14 Years**

(21) Appl. No.: **29/237,908**

(22) Filed: **Sep. 9, 2005**

(57) **CLAIM**

The ornamental design for a display with console for programmable logic controller, as shown and described.

DESCRIPTION

FIG. 1 is a front perspective view of a display with console for programmable logic controller showing our new design; FIG. 2 is a rear perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a right side elevational view thereof; FIG. 8 is a left side elevational view thereof; FIG. 9 is a front perspective view of the second embodiment of a display with console for programmable logic controller showing our new design; FIG. 10 is a rear perspective view thereof; FIG. 11 is a front elevational view thereof; FIG. 12 is a rear elevational view thereof; FIG. 13 is a top plan view thereof; FIG. 14 is a bottom plan view thereof; FIG. 15 is a right side elevational view thereof; and, FIG. 16 is a left side elevational view thereof.
